UNITED STATES PATENT OFFICE.

WILLIAM F. SMITH, OF EVANSTON, ILLINOIS.

CUFF.

Application filed September 2, 1924. Serial No. 735,434.

To all whom it may concern:

Be it known that I, WILLIAM F. SMITH, a citizen of the United States of America, and a resident of Evanston, county of Cook, and 5 State of Illinois, have invented a new and useful Improvement in Cuffs, of which the following is a specification.

This invention relates to garments and especially men's apparel. The main objects 10 of the invention are to provide an improved form of cuff; to provide for increasing both the life of the shirt and the period of clean appearance; to provide protective means on a cuff to prevent wear and soiling by contact with the wrist; to provide a shield member 15 on the inside of the cuff adapted to hold the main body of the cuff spaced away from the wrist; and to provide a cuff shield adapted to absorb within itself the moisture 20 and body salts from the adjacent skin of the wearer and so prevent staining the main cuff body.

An illustrative embodiment of this invention is shown by the accompanying drawings, in which:

Fig. 1 is a perspective view of a sleeve and cuff embodying this invention.

Fig. 2 is another perspective view showing the cuff in place on the wrist, but unbent to show the construction.

Fig. 3 is a fragmentary view of one end of the cuff showing the inner side.

Fig. 4 is a section on a larger scale, about full size, on the line 4-4 of Fig. 3.

In the construction shown in the drawings, the shirt sleeve has a cuff 1 permanently secured thereto as by sewing, the style here represented being known as the French cuff. A shield member 2 is secured to the 35 inside of the cuff adjacent to its outer edge, but spaced inward slightly therefrom, so as not to be noticeable when worn. This shield consists of a long narrow strip sewed to the inner fold 3 of the cuff, as by three parallel 40 seams at 4, 5 and 6 respectively, with the outer edge part 7, about an eighth of an inch, projecting free so as to stand out somewhat for effectually spacing the cuff body from the hand or wrist of the wearer. The 45 outer edge of the flap part 7 is preferably 50

about an eighth of an inch inward from the outer fold edge 8 of the cuff.

The shield 2 may be of similar material as the cuff 1 and is preferably so made. The inner edge of the shield 2 comes just below 55 the button-hole 10. The ends of the shield come about an eighth of an inch short of the cuff length at each end, as at 11. The shield may give a somewhat thickened and padded effect by folding the material upon 60 itself as will be understood.

The edge of the cuff is thus saved from contact with the wrist and hence wear is avoided at the point where shirts usually fail first. Moreover, the edge of the cuff is 65 where a shirt usually shows soiling first, but said shield protects it from picking up the body moisture, salts and grime from the wrist. By this means the foregoing purposes are accomplished.

Although but one specific embodiment of this invention has been herein shown and described, it will be understood that some of the details of the construction shown may be altered or omitted without departing 70 from the spirit of this invention as defined by the following claims.

I claim:

1. A cuff having a shield on its inner side adjacent to its outer edge but somewhat 80 short thereof and with the outer edge of said shield flared away from the body of the cuff.

2. A cuff having adjacent to its outer edge a long narrow strip, the back part of which is secured snugly throughout its length to 85 the cuff body and the front edge being free to insure effective spacing sufficient to prevent wear and soiling of the cuff edge by contact with the wrist or hand of the wearer.

3. A shirt cuff having attached to its inner side adjacent to its outer edge, in slightly spaced relation thereto, a shield strip, the inner part of which is stitched 90 snugly to the main body of the cuff and the outer edge being formed and adapted to 95 stand outward somewhat away from the cuff body.

Signed at Chicago this 9th day of August, 1924,

WILLIAM F. SMITH.
